UNITED STATES PATENT OFFICE.

CHRISTIAN GULBRANSEN, OF CHICAGO, ILLINOIS, ASSIGNOR TO GULBRANSEN COMPANY, OF CHICAGO, ILLINOIS, A CORPORATION OF ILLINOIS.

PLAYER PIANO.

Application filed October 16, 1924. Serial No. 743,866.

My invention relates to player pianos and more specifically to an improvement in the pneumatic stack of a piano.

Among the objects of the invention may be enumerated the minimizing of the volumetric capacity of the stack, and the simplification of the mechanical details of construction of the channel board and the pneumatics mounted thereon.

In the accompanying drawings, Fig. 1 is an end elevation partly in transverse section of a stack according to the invention;

Fig. 2 is a plan and Fig. 3 a central section of the valve block and valve for one of the unit pneumatics;

Fig. 4 is a face view of the grooved side of the channel board with part of the covering strips removed;

Fig. 5 is a section on the line 5—5 of Fig. 4; and

Fig. 6 is a section on the line 6—6 of Fig. 4.

In the embodiment of the invention selected for illustration, the face of the channel board 10, to which the unit pneumatics are to be attached, is left smooth. In the opposite face there is formed a small groove 12 hereinafter referred to as the bleed header and three somewhat larger grooves 14, 16 and 18, each forming a header for one of the tiers of pneumatics. As shown clearly in Figs. 5 and 6, these grooves extend into the channel board to somewhat less than half its thickness, leaving a solid portion adjacent the opposite face for the formation of independent passageways. At one end of the channel board branched tubes 20 communicate through holes 22 with headers 14, 16 and 18, and the branched tubes units into a single suction supply tube 24 which, for the purposes of the present invention, may be considered the source of suction for operating the stack.

The dimensions of headers 14, 16 and 18 are the minimum necessary to provide adequate communication between the source of suction and all the pneumatics on the stack. To facilitate making the headers of minimum size, I provide vertical cross connecting passages 26, three at the end of the channel board and others at uniform intervals throughout the length thereof. In case a large number of pneumatics all in the same tier should simultaneously be called into action by the note sheet, the headers for the

other tiers will furnish parallel paths of communication through passages 26. This makes it possible to use somewhat smaller headers than would otherwise be practicable. Cross passages 26 also form the sole source of supply for the bleed header 12, with which they communicate, as clearly shown in Fig. 4.

Supply passages for the individual pneumatics are formed at 28. By locating these so that they communicate with the lower edges of the headers, the pneumatics may be so positioned that the fastening screws 30 threaded into holding pins 32 to clamp each unit pneumatic in place on the channel board, may pass through an entirely solid portion of the board. This makes screws 30 a simple, mechanical fastening, entirely independent of the pneumatic passageways, and not directly concerned with any seal necessary to maintain the tightness of the pneumatic system. The washers 34 for screws 30 lie just below the lower edges of the sealing strips 35 for the headers.

The control passages for the individual pneumatics are formed near the smooth face of the channel board, being drilled in from the upper edge parallel to cross passages 26. Thus, in Fig. 4, the short passage 36 runs down to the first pneumatic, the next passage 38 runs down to the first pneumatic in the second tier, and the long passage 40 runs down to the first pneumatic in the bottom tier. By staggering the pneumatics as clearly shown in Fig. 4, it is easy to mis-match the holes. Thus passage 36 goes down between the supply passage and one of the screw holes for its pneumatic, passageway 38 passes the first tier between the same supply hole and the other screw hole, and passage 40 passes the upper tier between the screw holes for adjacent pneumatics, and passes the second tier between the supply passage and screw hole for the pneumatic operated through passage 38.

From header 12, a cross passage 42 runs to each control passage, said cross passages being substantially closed by metal cups 44 having accurately calibrated bleed orifices.

I prefer to connect the vertical control passages from the tracker bar to the smooth face of the channel board. For this purpose diagonal holes 46 are drilled in this face to connect with each vertical control channel, and metal nipples 48 may be inserted for

suitable connection with the flexible tubes running to the tracker bar.

Each pneumatic comprises a fixed leaf 50 and a hinged leaf 52 connected thereto by a 5 suitable fabric hinge 54. These leaves may be duplicates originally and differ in the finished pneumatic only by the formation of a hole 56 in the upper leaf and the affixing of a silencing and check pad 58 to the 10 upper surface of the lower leaf and an extension 60 to the lower surface to underlie the abstract 62.

To make it possible to employ leaves of the simple shape shown, it is necessary to 15 form both the valve chamber 64 and the diaphragm chamber 66 in the block 68. The block is accordingly provided with a large bore 70 of the proper diameter to receive the diaphragm 72, continued by a smaller bore 20 74 housing the disc 76 and easing pad 78 which carry the valve stem 80. Control passage 82 registers with the vertical control passage in the channel board, and opens below the diaphragm 72, while the inclined 25 supply passage 84 opens above the diaphragm and registers with the supply passage 28. Above the bore 86, housing valve stem 80, the block is enlarged to receive the lower valve seat 88, and again at 90 to form 30 the valve chamber 64, housing valve 92, movable between the lower seat 88 and the upper seat 93 attached to the top of the block 68. Vertical bores 94 and horizontal bores 96 in the corners of the block are formed 35 to receive holding pins 32 and fastening screws 30, respectively. From valve chamber 64 twin passages 100 lead to pocket 102 which registers with hole 56 in the fixed leaf.

It will be apparent that in the construction disclosed no machining of leaves 52 and 40 50, except the formation of the single hole 56 in the upper leaf is necessary, all the more intricate shapes being formed in block 68. This materially simplifies the process of 45 manufacture, and it is also possible, if desired, to use a different grade of wood for the leaves, as it is not necessary to have material in them that will stand machining into the intricate shapes formed in the block. 50 It should also be noticed that the block is the only element of the pneumatic engaging the face of the channel board. Both the supply and the control passages are formed in the block, and the inner end of the upper leaf 55 50 has no function to perform except receiving the hinge strip 54.

A single sealing strip 104 will form a complete seal for all the vertical passages in the channel board, both cross passages and 60 control passages; each of the pneumatic headers can be sealed by an individual sealing strip 35 and the bleed header 12 is sealed with crown strip 106. Certain portions of header 12 may be plugged with plugs 11 65 and the crown strip cut away to form points

of attachment for hinges. The formation of the diagonal passages 46 not only permits this simple seal to be used, but makes it possible to incline tubes 48, as clearly indicated in Fig. 7, at the most advantageous angle 70 for connection to the flexible tube running to the tractor bar.

Without further elaboration, the foregoing will so fully explain the gist of my invention, that others may, by applying current knowledge, readily adapt the same for use under various conditions of service, without eliminating certain features which may properly be said to constitute the essential items of novelty involved, which items are 80 intended to be defined and secured to me by the following claims.

I claim:

1. In a pneumatic stack, in combination, a channel board having three large grooves and one small groove formed in one face thereof, a direct connection to each large groove for delivering suction thereto, three tiers of unit pneumatics secured against the opposite face of said board and positioned to register with said large grooves, fastening screws for each unit pneumatic extending through solid portions of said board to the opposite side for convenient access, transverse equalizing passages extending in from one edge of said board to inter-connect all four grooves, transverse individual control passages extending in from the same edge past said grooves near the opposite face of said board to register with said unit pneumatics, bleed passages connecting each control passage with the small groove, tracker bar passages extending in at an angle from the ungrooved face of the board to said control passages, sealing strips covering all said grooves, and a sealing strip covering the ends of said equalizing and individual control passages.

2. In a pneumatic stack, in combination, a channel board having grooves formed in one face thereof, tiers of unit pneumatics secured against the opposite face of said board and positioned to register with each groove, transverse individual control passages extending in from one edge of said board past said grooves near the opposite face of said board to register with said unit pneumatics, an additional groove, and bleed passages connecting each control passage with said last mentioned groove.

3. In a pneumatic stack, in combination, a channel board having large grooves and one small groove formed in one face thereof, a direct connection to each large groove for delivering suction thereto, tiers of unit pneumatics positioned to register with said large grooves, fastening screws for each unit pneumatic extending through solid portions of said board to the opposite side for convenient access, transverse equalizing passages

- extending in from one edge of said board to inter-connect all four grooves, transverse individual control passages extending in from the same edge past said grooves near 5 the opposite face of said board to register with said unit pneumatics, bleed passages connecting each control passage with the small groove, tracker bar passages extending in at an angle from the ungrooved face of 10 the board to said control passages, sealing strips covering all said grooves, and a single sealing strip covering the ends of said equalizing and individual control passages.
4. In a pneumatic stack, in combination, 15 an integral channel board having rows of channels extending longitudinally therein and open at one face of said board, closure strips covering the open sides of said channels, and tiers of unit pneumatics secured 20 against the opposite face of said board and in alignment with said channels and connected with said channels through passageways extending transversely through said board.
5. In a pneumatic stack, a channel board 25 having a plurality of longitudinally disposed channels extending inwardly from one face of the board, closure strips secured to said face of the board and closing said channels, and pneumatic units secured on the opposite 30 face of the board and arranged in rows disposed in alignment with the respective channels, said board having air passageways extending from said opposite face thereof and 35 establishing direct communication between the respective pneumatic units and the channels of the board.
6. In a pneumatic stack, a one piece channel board having a plurality of longitudinally disposed channels extending inwardly from one face of the board, closure strips secured to said face of the board and closing said channels, pneumatic units secured on the opposite face of the board and arranged 40 in rows disposed in alignment with the respective channels, the board having an additional channel extending inwardly from the first mentioned face thereof, a closure strip over the outer side of said additional chan-
- nel, the board having passages extending 50 from one edge thereof and disposed between the channels and said other face of the board, said passages communicating with the pneumatic units and the board having bleed openings establishing communication between the passages and said additional channel, the board being further provided with 55 passages extending from said other face thereof and establishing direct communication between the respective units and the 60 channels, and means for connecting all of the channels to a suction source.
7. In a pneumatic stack, a channel board having a plurality of longitudinally disposed channels extending inwardly from one 65 face of the board, closure strips secured to said face of the board and closing the outer sides of the channels, pneumatic units at the opposite face of the board and arranged in rows disposed in alignment with the respective channels, said board having air passageways extending from said opposite face thereof and establishing communication between the respective units and the channels 70 of the board at the edge portions thereof, and securing members passing through the board from the first mentioned face thereof and between the channels, said members securing the pneumatic units to the opposite 75 face of the board.
8. In a pneumatic stack, a one piece channel board having a plurality of channels extending inwardly from one face of the board and disposed longitudinally thereof, strips closing the outer sides of the channels, 85 and pneumatic units at the opposite face of the board and arranged in rows disposed in alignment with the respective channels, each unit including a valve block secured to the board and a pneumatic secured to the block, the block having an air passage and the board having an air passage extending from 90 said opposite face thereof and establishing direct communication between the channel and the passage of the block.

In witness whereof I hereunto subscribe my name this 10th day of October, 1924.

CHRISTIAN GULBRANSEN.
